CLAIM

The ornamental design for a neck gasket for face soaking device, as shown and described.

DESCRIPTION

FIG. 1 may depict a perspective view of a neck gasket for a face soaking device;

FIG. 2 may depict a front view thereof;

FIG. 3 may depict a back view thereof;

FIG. 4 may depict a left-side view thereof;

FIG. 5 may depict a right-side view thereof;

FIG. 6 may depict a top view of thereof; and,

FIG. 7 may depict a bottom view thereof.

The broken lines showing some portions of a face soaking device are for the purpose of illustrating regions of the face soaking device that form no part of the claimed design.

1 Claim, 7 Drawing Sheets
